UNITED STATES PATENT OFFICE.

JAMES M. MAHER, OF FREMONT, NEBRASKA.

PROPELLER.

1,318,571.

Specification of Letters Patent.

Patented Oct. 14, 1919.

Application filed April 27, 1918. Serial No. 231,212.

To all whom it may concern:

Be it known that I, JAMES M. MAHER, a citizen of the United States, residing at Fremont, in the county of Dodge and State of Nebraska, have invented certain new and useful Improvements in Propellers, of which the following is a specification.

My invention relates to improvements in propellers and the main object of my invention is the propulsion of vessels on the ocean and other bodies of water, by my new and improved means at a greatly increased speed, and absolute certainty of movement.

Another object of my invention is the provision of means that can be applied to vessels already in use or under construction, and which will be positively practical and efficient for the intended purpose.

With these objects in view my invention consists of a system of propellers attached to the sides of vessels preferably recessed in the sides of the hulls of vessels, and operated from within the vessel by any desired power system.

The propulsion of a vessel to which my system of propellers is attached is caused by the outward, forward movement of vanes which consist of an upper and lower casing suitably, and at proper distances apart, partitioned, said partitions being partially oval in form, this shape being best suited to the engaging contact with the water; and, hinged to the inner end of said partitions, are auxiliary partitions, which also act as valves to operate automatically, opening on the inward stroke of the vanes, allowing the water to empty, and to close again at the forward movement of the vane.

This upper and lower casing partitioned vane, is operated by a power driven eccentric, suitably connected to the end of the vane; the opposite end of the vane being attached to a crank arm that moves in unison with the eccentric operating mechanism.

A plurality of vanes as above described, each attached to an eccentric on one end and a crank arm on the opposite end, may be used, the number depending on the speed of the vessel desired; thus a speed several times greater than is possible with the present means of vessel propulsion may be attained in this manner.

Another object of my invention is that each set of vanes, attached to opposite sides of the vessels, that is the right and the left set of vanes, while ordinarily working to-

gether in unison, may be quickly detached and either set work independently of the other, or one set remain idle, or reverse, while the other set continues propelling the vessel forward; thus this movement will rapidly turn the vessel to any desired angle, or around in a full circle if desired, or both sets of vanes may be used for zig-zagging the vessel; this and the speeding up the vessel is the primary object of my invention, to outdistance and zig-zag torpedoes.

Balance or fly wheels of sufficient weight and size will be attached to the vanes to steady and assist in carrying the vanes through the water, by their momentum, close to the upper end of the vertical crank arm and eccentric shafts.

Figure 1 is a side elevation of a vessel provided with my system of propellers.

Fig. 2 is an end view of my propelling mechanism.

Fig. 3 is a sectional plan or side view of the complete system of propellers and mechanism.

Fig. 4 is a top view of partitions, auxiliary partition and eccentrics and crank arms.

Fig. 5 is a sectional view taken on line 5—5 of Fig. 4.

Referring by numeral to the drawings in which similar numerals of reference denote the same parts in all of the views:

The numeral 1, designates the hull of the vessel of any type or character and my propelling mechanism is applied to each side of the hull at the most practical position, and one or more sets of the mechanisms may be used, but in the present drawing only one set is used.

The main aim of my invention is the provision of means which will consist of few working parts to insure simplicity, durability and inexpensiveness of production with full efficiency, and to the hull of the vessel either in recesses thereof or as shown in the drawings are mounted the pair of lateral extending brackets 2, having a series of arms 4, of varying lengths to present the bearings 5; in the outer ends thereof in line, and upon a proper place upon the brackets are formed or secured the fly or balance wheel casings 6.

In the bearings of the arms and casings are journaled the vertically disposed shafts 7, which near their upper ends carry the fly or balance wheels 8, and at their upper

ends the horizontally disposed bevel gear wheels 9, which mesh with the similar bevel gear wheels 10, arranged vertically upon the horizontal shaft 11, carrying intermediate 5 of its length the bevel gear wheel 12, meshing with the driving bevel gear wheel 13, on driving shaft 14, operated from a suitable source of power within the vessel.

From this construction it will be understood that the shaft from the vessel is revolved by any suitable power and revolves the horizontal shafts which in turn rotate the pairs of vertical shafts giving a high velocity or rotation to said shafts with the 10 balance wheels thereon, and one set of these shafts carries the pair of cranks 15, while the other set has mounted thereon the pair of eccentrics 16, which revolve in the pair of circular bands 17, on one end 18, of the 15 open heads 19, having their other ends 20, secured to the pairs of cranks 15.

The open heads 19 have mounted therein in a vertical position a series of curved vanes 21, the concave surfaces of which 20 form pockets for engaging the water and propelling the vessel when the heads are on their driving strokes. However when the heads 19 are returning to their initial driving positions, the convex surfaces of the 25 vanes 21, will prevent the vanes from materially reducing the headway of the vessel. Pivotally mounted in the heads 19, at the inner ends of the curved vanes are pivoted plates 22, the free ends of which engage the 30 abutments 21^a on the convex surfaces of the vanes 21, when the heads are on their driving strokes. These pivoted plates 22 are forced out of engagement with the abutments by the resistance of the water after 35 the completion of each driving stroke and are forced into engagement by the resistance of the water, when the eccentrics force the heads 19 outwardly for starting their driving strokes. It will be seen that the 40 curved vanes are completely braced by the pivoted plates 22 at all times when they are on a driving stroke.

It will thus be understood that my construction provides a propelling mechanism 45 which comprises few working parts which require a comparatively small amount of power to achieve the highest degree of efficiency, and that the one set of propellers are driving the vessel forward while the 50 other set is returning, and that such a mechanism is practical in every respect.

I claim:

1. A propulsion apparatus for vessels comprising a pair of brackets secured to the 55 side of a vessel, vertical shafts rotatably mounted in the brackets, one of said vertical shafts being provided with eccentrics in a horizontal plane, the other vertical shaft

being provided with cranks in a horizontal plane, connection bars having eccentric 65 yokes at one of their ends surrounding the eccentrics on the vertical shaft, the other ends of said connecting bars being pivotally secured to the cranks of the other vertical shaft, water engaging vanes carried by the 70 connecting bar for engaging the water and means for rotating the vertical shafts and the eccentrics whereby a reciprocating movement will be imparted to the connecting bars. 75

2. A propulsion apparatus for vessels comprising a pair of brackets secured to the side of a vessel, vertical shafts rotatably mounted in the brackets, one of said vertical shafts being provided with eccentrics 80 in a horizontal plane and at diametrically opposite sides of the vertical shaft, the other vertical shaft being provided with cranks in a horizontal plane, said cranks being at diametrically opposite sides of the vertical 85 shaft, connecting bars having eccentric yokes surrounding the eccentrics, the other ends of the connecting bars being pivotally secured to the cranks of the vertical shaft, water engaging vanes carried by the connecting bars for engaging the water and means for rotating the vertical shafts 90 whereby a reciprocating movement will be imparted to the connecting bars for propelling the vessel. 95

3. A propulsion apparatus for vessels comprising a pair of brackets secured to the side of a vessel, vertical shafts rotatably mounted in the brackets, one of said vertical shafts being provided with eccentrics 100 in a horizontal plane and at diametrically opposite sides of the vertical shaft, the other vertical shaft being provided with cranks in a horizontal plane, said cranks being at diametrically opposite sides of the vertical 105 shaft, connecting bars having at one of their ends eccentric yokes surrounding the eccentrics, the other ends of the connecting bars being pivotally secured to the cranks of the vertical shaft, water engaging vanes 110 carried by the connecting bars for engaging the water, pivotally mounted braces carried at the ends of the vanes and adapted to be thrown into and out of engagement with abutments on the vanes by the resistance of the water, means for rotating the vertical shafts whereby a reciprocating movement 115 will be imparted to the connecting bar for propelling the vessel and fly wheels carried by the vertical shafts. 120

In testimony whereof I affix my signature.

JAMES M. MAHER.
